UNITED STATES PATENT OFFICE.

JOHN KOZELKA, JR., OF STAFFORD SPRINGS, CONNECTICUT.

BOAT CONSTRUCTION.

Application filed July 17, 1926. Serial No. 123,108.

This invention relates to improvements in boats of the type in which a suitable motor is installed for propelling purposes. The propelling mechanism proper comprises in general, an endless chain which is located on the opposite sides of the boat to the alternate links of which are attached blades that engage the water for moving the boat forward or rearward. Located between the 5 blades is a link which is formed with an opening to receive the teeth of the driving gear wheels that are suitably geared to the motive power of the boat.

Devices for steering the boat are provided which comprises a drum around which is coiled a cable that extends to the opposite front sides of the boat. This cable is so connected and arranged as to simultaneously operate the two rudders in the same direction.

Referring to the drawings:

Fig. 1 is a plan view showing the motive power located within the boat, the gearing connection between the motor and the endless propeller chains, also the means for steering or guiding the boat.

Fig. 2 is a side elevation of Fig. 1 illustrating one of the rudders.

Fig. 3 is a plan view of a short section 30 of the propeller chain and one of the blades.

Fig. 4 is a side elevational view of Fig. 3.

Fig. 5 is an enlarged detail view of one of the driving gears.

Fig. 6 is an edge elevational view of Fig. 35 5, and

Fig. 7 is a detail of one of the supporting bearing blocks for the rudder.

Referring to the drawings in detail:

1 designates the body portion of the boat. 40 2 the driving motor of suitable type, as gasoline, like those used in motor vehicles. The transmission box 3 and bevel gearing 4 which transmits motion to the driving shaft 5 is shown in Fig. 1. This shaft is located in boxes 6. On the shaft 5 at its opposite ends is secured a gear wheel 7 shown in detail in Fig. 5 having the gear teeth 8 and flat surface 8'. Secured to the side of the boat are boxes 9 which may be 45 adjustable for supporting the shaft 10 on which a second gear wheel 11 like wheel 7 loosely turns. Passing around the gears 7 and 10 on each side of the boat is the propelling chain indicated as a whole by the 50 reference numeral 12. These chains are composed of the links 13 and 14 having

openings 15 and 16 to receive the teeth of the gears. The links are connected together by means of the pins 17, which pass through sleeves 18. The ends of the pins project 60 beyond the outer sides of the plates 19 and 20 where they are headed over. Located between the plates 19 and 20 are the propeller plates 21. They are secured to the plates by means of the rivets 22.

The openings 15 in the links 13 and the openings 16 in the links 14 are for receiving the teeth 8 of the gears 7 and 11, whereby the endless propeller chains 12 are actuated from the motor. Suitable clutch means is 70 operated by the rod 23. 24 is a cover which is attached to the side of the boat for preventing the water from being thrown over the edge of the boat when the propellers are operated.

For the purpose of steering or guiding the boat a pair of rudders are located on the opposite front sides of the boat as indicated at 25 and 26. 27 is a shaft, one end of which is located in the block 28 which 80 forms a bearing and the other end of the shaft has a bearing indicated at 29. 30 is a drum secured to the shaft 27 and 31 is the operating wheel. 32 are pulleys mounted on the upper ends of the shafts 33. 85 Attached to the lower ends of these shafts are the rudders 26, the shafts being supported in the bearing blocks 34 through which they pass as indicated by the opening 34'.

The advantages of locating the propeller chains on the opposite sides of the boats is that they assist in supporting the boat on even keel, the water line being indicated at 37. The plates 21 being secured to the 95 blades 19 are efficient in moving the boat forward, and, if the engine is reversed in stopping the boat, or, for propelling rearwardly. The securing of the plates between the blades 19 produces a very rigid propeller and the gear teeth 8 which enter the openings 15 and 16 have a long bearing on the flat surface 38 of the gear 8. The plates 19 and 20 further assist in maintaining the boat in a straight line since the water would 100 engage the sides of the blades.

The gear wheels 7 and 11 may, if desired, be formed as pontoons to assist in floating the boat.

The rod for operating the transmission 110 gears is indicated conventionally at 38.

What I claim is:

1. A propeller chain for the purpose described comprising a plurality of flat links with openings, means for pivotally connecting the links together, side plates secured to the alternate links, blades secured to the plates and located transversely of the plates.
5. 2. A motor boat construction comprising in combination, endless chain propellers located on the opposite sides of the boat, means for operating the propeller chains

comprising a shaft, a gear on the opposite ends, bearings in the sides of the boat for supporting the shaft, the chain having its alternate links provided with triangular shaped plates, blades secured to the said plates and projecting beyond the apices of the plates, said plates serving to maintain the motion of the boat in a straight line, as described. 15
